10 Claims. (Cl. 179—110)

The present invention relates to an electroacoustic transducer having as a diaphragm a flat vibrating plate which comprises at least one layer of electrostrictive material.

Transducers of this type have been known for a long time. However, they have not achieved any importance in actual practice since their sensitivity is too low as compared with the sensitivity of electroacoustic transducers of conventional type. It has already been attempted to increase the sensitivity of such transducers by taking into consideration the form of vibration caused in case of firm clamping of the vibrating plate, by means of a special arrangement of the electrodes, namely, an interruption thereof at the points of change of the direction of curvature of the diaphragm, and in addition, by reducing the thickness of the plate to less than 0.01 millimeter in order better to match the diaphragm to the characteristic impedance of the surrounding acoustic medium, by applying the electrostrictive material by volatilization to a thin support. Such transducers, however, likewise have not gained acceptance up to now. In particular, the application of a homogeneous electrostrictive layer in the necessary thickness, by volatilization, produces considerable difficulties from a manufacturing standpoint.

The present invention shows how the sensitivity of electrostrictive transducers of the initially noted type can be increased without it being necessary to reduce the thickness of the plate to such an extent that it becomes difficult to manufacture.

The object of the invention is realized by smoothing the surface of the electrostrictive material which lies below the contact material, and by holding the vibrating plate at the edge between a fixed support and a resilient support.

This arrangement is based upon recognition of the fact that it is not sufficient for the electrostrictive material merely to be ground, particularly in the case of a small thickness of the plate. The scorings produced by the grinding cause a crowding of the lines of force at the notch-like interruptions in the electrostrictive material, upon the polarization of the material, thus resulting in an excessive heating at these points. Upon unlimited polarization current, this will lead finally to a disruptive discharge, while with limited polarization current, the voltage breaks down between the electrodes of the electrostrictive material so that it is no longer sufficient to impress a sufficiently high polarization field strength in the rest of the electrostrictive material.

It is for sufficient polarization important, in addition to a homogeneous electrostrictive material and a uniform thickness of the plate, to provide as smooth as possible a surface of the electrostrictive material below the electrodes through which the polarization voltage is applied.

The vibrating plate of the transducer of the present invention comprises preferably two smooth contacted disks of electrostrictive material which are about 0.2 millimeter thick and bonded or soldered together. Such disks can be made by grinding and subsequent lapping, from thicker plates, which can be produced in a particularly homogeneous, stress-free and crack-free manner. They have the advantage over extremely thin plates of electrostrictive material that they are easier to manufac-

2

ture, that the resistance against breakage is greater, that unavoidable small discontinuities, such as inhomogeneity of the material, inclusions of foreign bodies, hair cracks, etc., exert a smaller percentual effect and that the natural vibration lies in the upper part of the transmission range. While matching to the surrounding acoustic medium is better in the case of extremely thin vibrating plates, the natural vibration lies in the lower part of the transmission range. As a result, the transmission range drops so greatly in the upper part that upon linearization of the frequency response, the increase in sensitivity obtained by the better matching is necessarily lost.

In the arrangement provided by the present invention, an increase in sensitivity is obtained not only by the provision of a surface which is as smooth as possible, namely, having a roughness of not more than 5 microns, resulting in increased polarization, but also by the particular nature of the mounting of the vibrating plate. The mounting is so constructed that the vibrating plate oscillates like a plate which rests freely on its edge. For a given thickness of the plate, this means an increase in sensitivity by about a factor of 3.2, as compared with the fixed mounting used heretofore in electrostrictive transducers. The lesser stiffness of the resilient clamping also results in better matching to the characteristic impedance of the surrounding acoustic medium.

For the desired increase in sensitivity, it is also advisable that the metal coatings of the electrostrictive disks do not extend up to the edge thereof, but leave an electrode-free edge zone. The form of oscillation which occurs with the mounting of the diaphragm in accordance with the invention, can thereby be taken into consideration. It was found in this connection that the sensitivity is greatest with a diameter of the metal coatings equal to about 0.91 times the diameter of the annular fixed support. A combination of all the aforementioned measures results in a sensitivity which reaches a value corresponding approximately to that of the sensitivity of electroacoustic transducers of the traditional type.

The invention will be explained in further detail with reference to the accompanying drawing.

FIG. 1 shows part of an electroacoustic transducer which is of interest in connection with the invention;

FIG. 2 shows a modified mounting for the diaphragm; and

FIG. 3 shows a further modified mounting for the diaphragm.

In FIG. 1, numeral 1 indicates the housing of the electroacoustic transducer which is closed by a cover 2. The transducer has a plate-shaped diaphragm 3 which comprises two layers 4 and 5 of electrostrictive material and is held between a rigid support 6 and a resilient support 7. The rigid support is made in the form of a protrusion of trapezoidal cross-section in the wall of the housing. The resilient support is made as a ring of resilient material, such as soft rubber, foam, thermoplast, etc. The cross-section of this ring has in this case also a trapezoidal shape. However, it could just as well be rectangular, since it is to consist of such a soft material that it will not interfere with the movement of the diaphragm regardless of its resting surface against the diaphragm. The two electrostrictive layers of the diaphragm are in each case metallized on both sides and bonded or soldered together. In order that the desired movement of the diaphragm be obtained, the two electrostrictive layers are polarized axially in the same direction and the two metal coatings 8 and 9 which lie against each other and the outer coatings 10 and 11 of the diaphragm are in each case connected with each other and connected with an electrical terminal. The metal coatings do not cover the entire surface of the electrostrictive material but only about nine-tenths of the diameter of

the annular stationary support. The edge is thus maintained inactive.

In the embodiment shown in FIG. 2, the stationary support 12 is made in the form of a sharp-angled protrusion with rounded edge in the wall of the housing. The opposite support consists of a resilient metal ring 13 which is made in desired known manner and rests against the housing cover or is fastened to it.

In the embodiment shown in FIG. 3, the stationary support is made in the form of a non-yieldable metal ring 14 of circular cross-section, while the resilient support is made in the form of a soft rubber ring 15.

Changes may be made within the scope and spirit of the appended claims which define what is believed to be new and desired to have protected by Letters Patent.

We claim:

1. An electroacoustic transducer having a diaphragm in the form of a vibrating plate, said plate comprising at least one disk of electrostrictive material, a layer of a conductive contact material disposed on each face of the disk, the surface of the electrostrictive material disposed beneath such contact material having a roughness of at most about 5 microns, and means for supporting said vibrating plate at its edge, said means having a stationary supporting element and a resilient supporting element, between which elements said plate is disposed.
2. An electroacoustic transducer according to claim 1, wherein the disk of electrostrictive material is about 0.2 millimeter thick and is provided with ground and lapped surfaces.
3. An electroacoustic transducer according to claim 1, wherein the vibrating plate consists of two electrostrictive circular disks which are metallized on both sides and bonded together, and wherein the diameter of at least the

two outer metal coatings of the vibrating plate is less than the diameter of the stationary support thus leaving a coating-free outer edge.

5. An electroacoustic transducer according to claim 3, wherein the diameter of at least the two outer metal coatings of the vibrating plate is about 0.91 times the diameter of the annular stationary support.

10. 6. An electroacoustic transducer according to claim 4, wherein the stationary support is part of the housing wall in the form of a projection of trapezoidal cross-section.

15. 7. An electroacoustic transducer according to claim 4, wherein the stationary support is part of the housing wall in the form of an acute-angled projection with rounded edge.

20. 8. An electroacoustic transducer according to claim 7, wherein the resilient support is a ring of resilient material, selected from the class of materials consisting of soft rubber, foam material, thermoplast and the like.

25. 9. An electroacoustic transducer according to claim 6, wherein the resilient support is a metal ring having resilient properties.

10. 10. An electroacoustic transducer according to claim 9, wherein said metal ring is fastened to the housing cover.
